UNITED STATES PATENT OFFICE.

ALVIN C. McCORD, OF CHICAGO, ILLINOIS.

PRESSED-STEEL JOURNAL-BOX.

1,149,274.

Specification of Letters Patent. Patented Aug. 10, 1915.

Application filed February 8, 1915. Serial No. 6,789.

To all whom it may concern:

Be it known that I, ALVIN C. McCORD, a citizen of the United States, residing at Chicago, in the county of Cook and State of Illinois, have invented certain new and useful Improvements in Pressed-Steel Journal-Boxes; and I do hereby declare the following to be a full, clear, and exact description of the invention, such as will enable others skilled in the art to which it appertains to make and use the same.

Particularly, my invention has for its object to provide an improved all pressed steel journal box in which the box proper may be stamped or pressed from a single piece of sheet steel, and to such ends, generally stated, the invention consists of the novel construction and combination of parts hereinafter described and defined in the claims.

The invention involves two main novel features and certain other important minor features.

The first of the said main novel features consists in forming the cellar and top of the box from a single piece of sheet steel, by providing integral extensions from the side-forming portions of the sheet and bending these, one over the other, and overlapping the same to form the top or roof of the box. This construction not only reduces the number of parts of the box but provides a very strong top in which the overlapped inner and outer top forming plates will be held together by the weight or pressure on the top of the box, and thereby very greatly reducing the necessity of welding or otherwise connecting the said top plates.

The second principal novel feature consists in forming the pressed steel cellar of the box with an integral inwardly-pressed corrugation or rib that constitutes the inside dust guard wall. This dust guard wall may be produced as a part of the operation required to press the sheet into the form of a cellar, and hence, reduces the cost, eliminates the necessity for welding and provides an oil-tight joint which will prevent leakage of oil from the cellar into the dust guard seat.

In the accompanying drawings which illustrate the invention, like characters indicate like parts throughout the several views.

Referring to the drawings: Figure 1 shows one form of blank from which the journal box may be constructed; Fig. 2 is a side elevation showing the complete jour-

nal box constructed from the blank shown in Fig. 1; Fig. 3 is a view partly in section and partly in elevation looking at the outer end of the box shown in Fig. 2; Fig. 4 is a vertical section taken through the box on the line $x^4 x^4$ on Fig. 3; Fig. 5 shows the said box partly in plan and partly in horizontal section; Fig. 6 is a transverse section taken on the line $x^6 x^6$ on Fig. 4; Fig. 7 shows a blank quite similar to, but differing somewhat from the blank shown in Fig. 1; Fig. 8 is a plan view of the box constructed from the blank shown in Fig. 1; Fig. 9 is a vertical section taken on the line $x^9 x^9$ on Fig. 8; Fig. 10 is a transverse section taken on the line $x^{10} x^{10}$ on Fig. 8; Fig. 11 is a transverse section taken on the line $x^{11} x^{11}$ on Fig. 8.

First note the construction illustrated in Figs. 1 to 6, inclusive. From the blank stamped as shown in Fig. 1, the cellar or body 1 of the box is pressed into the form shown in Figs. 2 to 6, inclusive. Here it may be noted that the bending lines of the blank, Fig. 1, are indicated by dotted lines marked y , y^1 , y^2 , y^3 and y^4 . The side forming portions of the box are between the bending lines y and y^1 . The plate 2 is bent on line y^1 and constitutes the inner top forming plate, and it is bent on the line y^2 to form a depending flange 2^a that engages against the inner upper surface of one side of the cellar. By bending on the inner line y^2 , the outer top forming plate 3 is extended over the entire top of the box and is brought down against and overlapped with the said inner top plate 2; and by bending on the lines y^4 , depending flanges are provided which overlap with the outer upper surfaces of the sides of the box. The cellar 1 is provided with depressed bosses 4 that flatten the bottom thereof for engagement with the lower arch bar, and in approximately the same transverse vertical plane, the side-forming portions of the cellar are provided with inwardly-pressed bosses or bulges 5 that afford center brass-stops. On a proper transverse line between the bosses 4 and the inner end of the box, the blank is formed with a deeply pressed rib or corrugation 6 that extends across the bottom and well up the side-forming portions of the sheet, and which, when the cellar is pressed into shape, has a segmental form, as best shown in Fig. 6, and constitutes the inside dust guard wall of the box. By bending the narrow portions

- of the blank, Fig. 1, on the lines y^2 y^2 upon themselves, and thence downward against the sides of the box, as best shown in Fig. 3, the box is provided with outwardly projecting lugs 7 that are perforated at 8, so as to pass the arch bar bolts. At its transversely central outer end portion, the outer top forming plate 3 has an integral upwardly pressed hollow lid hinge lug 9 that may be of a form suitable for application of a lid of any desired type. On each side of the hinge lug 9, the said inner top plate 2 has abrupt depressions 10 that serve as outer wedge stops. At its extreme inner end edge, the outer plate 3 projects beyond the inner plate 2 and is formed with a transversely elongated dust guard opening 11, preferably located in an upwardly bulged portion on the said plate, but in any event, properly positioned in respect to the integral inside dust guard wall 6, so that the dust guard (not shown) will be properly positioned between the same and the inner end flange 12 of the cellar. The depending flanges on the top forming plates 2 and 3, which overlap the sides and inner end of the cellar, would usually be connected by spot-welding, and if desired, said plates 2 and 3 may also be spot-welded. Approximately in line with the arch bolt lugs 7, the top plate 3 is formed with one or more raised corrugations 13 which increase the strength of said plate and afford a suitable top arch bar seat.
- The construction illustrated in Figs. 7 to 11, inclusive, is very much like that illustrated in Figs. 1 to 6, inclusive, but differs therefrom in that both of the top-forming plates 2 and 3 are directly united to the cellar forming portion of the blank, and the reduced portion 14, which forms the top arch bar seat or seating yoke, is projected entirely from one side of the outer top-forming plate 3. In forming the box from the blank 7, the outer plate 3 is folded on top of the inner plate 2, as noted in the description of the formation of the box from the blank 1, and thereafter, the arch bar seating yoke 14 is bent on the lines marked x^1 x^2 , to thereby cause the said yoke to project and serve as arch bar lugs, and which lugs are provided with suitable bolt holes 15. Otherwise than noted, the box shown in Figs. 8 to 11, may be assumed to be identical with that shown in Figs. 2 to 6, inclusive, although the lid hinge lug 9^a which is pressed from the other top-forming plate 3, as illustrated, differs from the lug 9 in the particulars not necessary for the purposes of this case to consider.
- What I claim is:
1. A pressed sheet metal journal box having integral extensions from two of its wall-forming portions, overlapped with each other to form one of the other walls of the box.

2. A pressed sheet metal journal box having integral extensions from its side-forming portions, overlapped with each other and forming the top of the box.
3. A journal box constructed from a single piece of sheet metal, having extensions from its side wall-forming portions, overlapped with each other and each spanning the box and together forming the top of the box.
4. A journal box constructed from a single piece of sheet metal having extensions from its side wall-forming portions, overlapped with each other and each spanning the box, one of said top forming extensions having a lid hinge lug pressed upward therefrom at the outer end of the box.
5. A journal box constructed from a single piece of sheet metal having integral extensions from its side wall-forming portions, overlapped with each other and each spanning the box and together forming the top of the box, one of said top-forming extensions having a dust guard opening at the inner end of the box.
6. A journal box constructed from a single piece of sheet metal having extensions from its side wall-forming portions, overlapped with each other and each spanning the box and together forming the top of the box, one of said top-forming extensions having depressions constituting outer wedge stops.
7. A journal box constructed from a single piece of sheet metal having integral extensions from its side wall-forming portions, overlapped with each other and each spanning the box and together forming the top of the box, the upper of said overlapped top-forming extensions having an upwardly pressed lid hinge lug, at the outer end of the box, and having a dust guard opening at the inner end of the box.
8. A journal box constructed from a single piece of sheet metal having extensions from its side wall-forming portions, overlapped with each other and each spanning the box and together forming the top of the box, the outer of said overlapped top-forming extensions having an upwardly depressed lid hinge lug, at the outer end of the box, and having a dust guard opening at the inner end of the box, said inner of said top-forming extensions having depressions affording outer wedge stops, and the sides of said box having inwardly bulged portions constituting center wedge stops.
9. A pressed sheet metal journal box cellar having at its inner extremity a flange affording an outside dust guard wall, and the said cellar having an upwardly and inwardly pressed integral corrugation affording an inside dust guard wall and coöperating with said outside dust guard wall to form a dust guard seat at the bottom of the cellar.
10. A pressed sheet metal journal box cel-

- lar having an approximately semi-cylindrical bottom, provided at its inner extremity with a flange affording an outside dust guard wall, the bottom of said cellar having a segmental inwardly and upwardly pressed integral corrugation affording an inside dust guard wall and coöperating with said outside dust guard wall to form a dust guard seat at the bottom of the cellar.
- 10 11. A pressed sheet metal journal box provided with a dust guard opening in its top and having, in the body of its cellar, an in-

tegral inwardly-pressed corrugation, affording an inside dust guard wall, and formed with an integral inner end flange coöperating with said inside dust guard wall to form a dust guard seat at the bottom of the box. 15

In testimony whereof I affix my signature in presence of two witnesses.

ALVIN C. McCORD.
